NAIL SET HOLDER

Henry B. Simmons, Los Angeles, Calif.

Application August 18, 1955, Serial No. 37,573

Term of patent 7 years

(Cl. D93—2)

I claim:

The ornamental design for a nail set holder, substantially as shown.
